RETARDING MEANS FOR RAILWAY CAR DOORS

James S. Swann, Homewood, Ill., assignor, by mesne assignments, to Standard Railway Equipment Manufacturing Company, a corporation of Delaware

Application September 2, 1941, Serial No. 409,187

3 Claims. (Cl. 292—68)

The invention relates to doors for railway cars and more particularly to means for preventing violent and unrestricted movement of a sliding door during service movements of the car. The usual type of sliding side door is well known in the railway car art wherein a door is movable on a track substantially parallel with the wall of the car and moves into and out of alignment with the doorway in the side wall.

Various means for supporting and moving such a sliding door are used. One of the best known is that disclosed in Gilpin Patent No. 1,902,772 of March 21, 1933, wherein rollers are rotatably mounted upon the door and a track engaged by such rollers is rigidly carried by the car. The track is provided with depressions located at the proper places so that when the door is in the full open or full closed position, the rollers are above the depressions. The rollers are thus relieved of the weight of the door and in their place the door is supported by engagement of rigid parts carried respectively by the door and car. The friction between such rigid parts tends to prevent movement of the door.

In recent years a combination of circumstances, such as increased train and switching speeds and heavier loading of cars, has tended to impart more violent shocks to cars during service with the result that the above mentioned frictional resistance as well as other retarding means sometimes used have become inadequate to prevent accidental door movement. Such movements are liable to cause damage to the car and to the door, as well as injury to an operator who happens to get in the way of such a moving door.

An object of my invention is to provide a retarding means for a railway car door which is operative in the full open and full closed position and in any intermediate position for preventing unrestricted and violent accidental door movements during the operation of the railway car.

Another object is to design such retarding means so that it may be easily operated by a simple operation.

A further object is to provide a simple, rugged and inexpensive retarding means which may be easily adapted to any of the conventional designs of railway car side doors now in service.

Another object is to associate a handle with the above mentioned retarding means so that when a force sufficient for moving the door is exerted upon the handle, the retarding means is automatically adjusted so as to release the door for easy movement.

Another object of my invention is to provide a retarding means which may be released by either the operator's hand or foot. It is sometimes desirable that an operator open the car door when standing on the ground and for this purpose a handle is operatively connected to the retarding means so that a force on such handle sufficient to move the door releases the retarding means and makes the door easily movable. On the other hand, cars are often placed adjacent platforms which are substantially at the level of the car floor. In such a case, an operator standing on the platform may push a rigid handle located at arm height and at the same time step on a treadle associated with the retarding means, thereby releasing the door for easy movement.

Other objects and advantages of my invention will be apparent from the following detailed description by referring to the accompanying drawings.

In the drawings:

Fig. 1 is a partial side elevation of a railway car showing one embodiment of my invention.

Fig. 2 is an enlarged view of the retarding means shown in Fig. 1.

Fig. 3 is a section on line 3—3 of Fig. 2.

Fig. 4 is a plan view of the retarding means as indicated by the line 4—4 of Fig. 2.

Fig. 5 is a view of a portion of the retarding means shown in such a position that the door is locked to prevent movement toward the right.

Fig. 6 is a view similar to Fig. 2 showing the retarding means released so as to permit free movement of the door.

Fig. 7 is a view similar to Fig. 2 showing a modified form of my invention.

Fig. 8 is a section on line 8—8 of Fig. 7.

Fig. 9 is a section on line 9—9 of Fig. 7.

In Fig. 1, the side wall 2 has a door opening and a side door 3 is shown in position wherein it completely closes the doorway. The track 5 for supporting the door 3 is a longitudinally extending, inwardly facing channel member preferably secured to the side sill 6 of the car. A roller housing 8 is rigidly mounted upon each of the lower corners of the door 3; rollers 9 are rotatably mounted within the housings 8 and arranged to roll upon the upper laterally extending flange 11 of the channel track 5. The track 5 is provided with spaced apart depressions 12 arranged so that when the door is in the full closed or full open position, the rollers 9 are above the depressions 12. The rollers 9 are thus relieved of the weight of the door, which weight is taken by rigid parts of the roller housings 8 or other

rigid parts of the door which engage the track. The friction between such parts and the track retards movement of the door. The starting lever 14 is pivoted (16) to the door 3 and has its lower end 15 arranged to engage a starting bracket 17 secured to the track 5 for the purpose of utilizing the leverage to move the rollers 9 out of the depressions 12. Such a starting lever is more fully disclosed in Schlesinger Patent No. 1,963,152, June 19, 1934.

The retarding means is comprised in part by a base 20 rigidly secured to the door 3 and having a part 21 thereof offset outwardly from the door. The movable dog 23 has a vertically extending slotted hole 24 in the shank thereof and a pintle 27 rigidly attached to the offset part 21 of the base 20 extends through the hole 24 and supports the dog 23 for both sliding and pivotal movement. The lower part of the dog 23 is offset inwardly to form an upper lug 29 which preferably rests in its normal position upon the upper flange 11 of the channel track member 5. The dog 23 is also provided with a lower lug 30 spaced below the upper lug 29 and disposed underneath the upper track flange 11. The dog 23 is also provided with an outwardly projecting embossment 32 disposed below the slotted hole 24.

As shown in Fig. 2, the retarding means, including the dog 23, is in the normal, at rest position. When the door 3 is moved toward the right, the friction between the upper lug 29 and the upper flange 11 of the channel track member 5 causes the dog 23 to rotate about the pintle 27 until the dog 23 assumes the position shown in Fig. 5. In this position, one edge 35 of the upper lug 29 and the opposite edge 36 of the lower lug 30 grip opposite sides of the upper track flange 11 and prevent further movement of the door toward the right. If the door 3 is moved toward the left a limited distance, the dog 23 rotates in the counter-clockwise direction and grips the track 5 in a similar manner. The lower surface 38 of the upper lug 29 is preferably convex downwardly so as to facilitate pivotal movement of the dog 23. When it is desired to move the door, the dog 23 is lifted by a means herein-after described to the position shown in Fig. 6 wherein both the upper (29) and lower (30) lugs are free of the upper flange 11 of the track 5 and no gripping action will take place.

A lever 40 is pivotally mounted upon the door 3, preferably by a rivet 41 through the lower door frame strip 43. The right hand end 44 of the lever 40 is flared outwardly and engages the lower side of the embossment 32. The left hand end of the lever 40 is formed in the shape of a treadle 46 intended for operation by the foot of the operator. A rigid stop member 47 is mounted upon the door 3 to limit downward movement of the left hand end of the lever 40. When a man is standing on a platform or other floor level support, a pressure by his foot upon the treadle 46 lifts the dog 23 to the position shown in Fig. 6 and the door is then freely movable in a horizontal direction along the track 5.

The handle 50 is pivoted (51) at its upper end to the door 3 for swinging movement in a plane substantially parallel to the plane of the door. The lower end of the handle 50 is provided with a horizontally extending slotted hole 53 which receives a rivet 54 mounted rigidly upon the door, thereby limiting the pivotal movement of the handle 50 about its upper pivot 51. The left hand end of the lever 40 is provided with an inverted V-shape upstanding cam 56. The lower

end of the handle 50 is also provided with a cam 57 substantially complementary to the cam 56 on the lever 40 and normally engaged therewith in the position shown in Fig. 2. An operator standing upon the ground, when he desires to move the door 3 horizontally, grips the central part 59 of the handle 50 and exerts a force in a substantially horizontal direction. This imparts a limited pivotal movement to the handle 50 and the cams 56, 57 engage to deflect the left hand end of the lever 40 downwardly, thereby lifting the dog 23 and releasing the door for movement, as shown in Fig. 6.

In the modification shown in Figs. 7 to 9, 15 a U-shape bracket 60 is rigidly attached to the door 3 and the handle 61 is pivotally mounted upon the bracket 60 in such a way as to swing about a horizontal axis substantially parallel to the plane of the door. As is common in a car 20 of the type disclosed, a threshold reinforcing angle 63 is provided and the threshold plate 64 is bent around and overlaps both the upper and lower sides of the horizontal leg 66 of the reinforcing angle 63. The depending vertical leg 69 25 of the reinforcing angle 63 is provided with a plurality of horizontally spaced holes 70.

The lower end of the handle 61 has rigidly mounted thereon a pin 72 extending inwardly from the handle 61 through a hole in the lower door frame strip 73. A trapezoidal guide block 75 is mounted upon the lower door frame strip 73 and has a hole for guiding the inner part of the pin 72. The pin 72 is adapted to be inserted into one of the holes 70 in the angle 63, 30 according to the position of the door 3. A helical spring 76 concentric with the pin 72 is retained between the lower door frame strip 73 and a vertically extending cotter key 78 carried by the pin 72. The helical spring 76 thus functions to yieldingly hold the handle 61 close to the door sheathing 79 and thereby also yielding holds the inner end of the pin 72 against the vertical leg 69 of the reinforcing angle 63 so that when the pin 72 becomes aligned with one 35 of the holes 70, the pin 72 will become inserted in such hole 70 and the door 3 will be locked against further horizontal movement. It is pointed out that when the handle 61 is in the locking position shown in Fig. 8, the clearance 40 between the central part 81 of such handle 61 and the door sheathing 79 is not sufficient to accommodate the hand of the operator. Therefore, in order to get a grip on the handle 61 sufficient to push the door, the operator must 45 be of necessity move the handle 61 outwardly and thereby remove the pin 72 from one of the holes 70 in the reinforcing angle 63. This eliminates the possibility of the operator trying to move a door that is locked.

A lever 85 is pivotally mounted upon the lower door frame strip 73 to swing about an axis substantially normal to the plane of the door 3. The right hand end of the lever 85 is formed with a treadle 88 as hereinbefore described. The left hand of the lever 85 is provided with an inclined cam surface 89, as shown in detail in Fig. 9. A horizontally extending lug 91 is carried by the lower part of the handle 61 and engages the cam surface 89 of the lever 85, as 50 shown in Fig. 9. When the car is near a platform the operator, in order to move the door exerts a horizontal force preferably upon a rigid handle mounted at arm height and at the same time steps upon the treadle 88. The stepping upon the treadle 88 moves the left hand end of

the lever 85 upwardly. Such movement moves the lower end of the handle 61 outwardly and the pin 72 is disengaged from a hole 10; the door 3 is thereby unlocked and may be easily moved.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. Retarding means for a door of a railway car, said door movable along a track having a laterally extending part and carried by said car; said means comprising a dog slidably and pivotally mounted upon said door and comprising vertically spaced lugs disposed respectively above and below said laterally extending part so that upon pivotal movement of said dog said lugs bind upon said part and retard movement of said door along said track, a lever pivotally mounted upon said door in engagement with said dog so as to raise the dog upon rotation of said lever to prevent said binding, a handle pivotally mounted upon said door for moving said door along said track, and cam means between the handle and the lever for rotating said lever upon pivotal movement of said handle, whereby said dog may be raised and said retarding means released by a force exerted upon said handle.

2. Retarding means for a door of a railway

car, said door movable along a track having a laterally extending part and carried by said car; said means comprising a dog slidably and pivotally mounted upon said door and comprising vertically spaced lugs disposed respectively above and below said laterally extending part so that upon pivotal movement of said dog said lugs bind upon said part and retard movement of said door along said track, a lever pivotally mounted upon said door in engagement with said dog so as to raise the dog upon rotation of said lever to prevent said binding, and a treadle on said lever to rotate said lever, whereby said dog may be raised and said retarding means released by a force exerted upon said treadle.

3. Retarding means for a door of a railway car, said door movable along a track having a laterally extending part and carried by said car; said means comprising a dog slidably and pivotally mounted upon said door and comprising vertically spaced lugs disposed respectively above and below said laterally extending part so that upon pivotal movement of said dog said lugs bind upon said part and retard movement of said door along said track, a lever pivotally mounted intermediate the ends thereof upon said door, one end of said lever being in engagement with said dog so as to raise the dog upon depression of the other end of said lever to prevent said binding and thereby release the door for movement along said track.

JAMES S. SWANN.
